CLAIM

The ornamental design for a spherical lock, as shown and described.

DESCRIPTION

FIG. 1 is a front, right, top perspective view of a spherical lock showing our new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof;

FIG. 9 is an enlarged view of the bounded area 9 of FIG. 1;

FIG. 10 is an enlarged view of the bounded area 10 of FIG. 2; and,

FIG. 11 is an enlarged view of the bounded area 11 of FIG. 3.

The broken lines shown on the drawings depict portions of the spherical lock that form no part of the claimed design. The dot-dash lines depict the enlarged view boundaries that do not form part of the claimed design.

1 Claim, 11 Drawing Sheets
